REFRIGERATOR AIR CIRCULATING AND
PURIFYING MEANS

Herbert H. Short, Fort Collins, Colo.

Application March 5, 1938, Serial No. 194,189

9 Claims. (Cl. 62—89)

This invention relates to the class of refrigeration and pertains particularly to improvements in air circulating means.

The present invention has for its primary object to provide a unit for a mechanical refrigerator which may be built into the refrigerator when the same is constructed or may be installed in an already constructed refrigerator and which is designed to control the circulation of refrigerated air whereby a more thorough distribution of the air through the refrigerator will be effected.

Another object of the invention is to provide in an air circulation controlling unit for mechanical refrigerators, a means for removing absorbed gases from the air of the refrigerator thereby eliminating to a certain extent the carrying of odors from one article of food to another.

Still another object of the invention is to provide in an air circulation controlling mechanism for a mechanical refrigerator, a novel means forming a part of the mechanism for spreading out the refrigerated air over the bottom of the food chamber of the refrigerator whereby the previously referred to thorough distribution of chilled air is effected.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:—

Figure 1 is a view illustrating conventionally the front elevation of a mechanical refrigerator from which the door has been removed and showing the application thereto of mechanism embodying the present invention.

Figure 2 is a sectional view taken on the line 2—2 of Figure 1, looking downwardly toward the air distributing portion of the mechanism.

Figure 3 is a sectional view taken on an enlarged scale substantially on the line 3—3 of Figure 2.

Figure 4 is a vertical section taken through the air purifying unit of the mechanism, the section being substantially on the line 4—4 of Figure 5.

Figure 5 is a sectional view taken across the air purifying unit at right angles to the section of Figure 4 and substantially upon the line 5—5 of Figure 4.

Referring now more particularly to the drawing, the numeral 1 generally designates a refrigerator of the mechanical type wherein there is provided the food chamber 2, the refrigerating unit 3 within the food chamber, and a chamber 5 for housing the power mechanism such as the motor and compressor units, such a chamber being here designated generally by the numeral 4 and shown as being at the lower part of the refrigerator structure. Since the freezing unit and the 10 motor and compressor units form no part of the present invention, the latter has not been illustrated and the freezing unit has only been conventionally outlined.

Within the food chamber are the usual shelves 5 15 and disposed above the uppermost one of these shelves and at the side of the freezing unit 3, is an air purifying unit forming a part of the present invention and generally designated by the numeral 6. This air purifying unit comprises a 20 casing 7 having the front and back walls 8 and 9 respectively, and a top wall 10 which connects the front and back walls, as shown in Figure 4. Within this casing is a receptacle 11 which extends between the front and back walls 8 and 9 25 and has a rounded bottom 12, as shown in Figure 5, and has the top edges of its side walls 13 cut away to form apertures 13a so as to provide air passageways, as shown. Extending down through the center of the receptacle 11 is a frame 30 14 which reaches nearly to the bottom of the receptacle and which has therein a filler of absorbent material, which is indicated by the numeral 15, and which is woven in such a manner that air currents may pass therethrough. 35

Upon either side of the absorbent screen within the receptacle 11, is a baffle plate 16 which also extends downwardly from the top wall 10 of the air deodorizing unit but terminates a substantial distance above the lower edge of the frame 14. 40 In use, the receptacle 11 is filled with a suitable liquid to a level just below the lower edges of the plates 16.

The numerals 17, 18 and 19 designate air ducts which provide air passageways around the refrigerating unit 3 to conduct air from the opening 13a which is nearest the refrigerating unit, to the downwardly extending air-duct 20. It will thus be seen that the duct 20 and the duct 17 are in parallel relation, and the ducts 18 and 19 are horizontal and connect the two vertical ducts 17 and 20 so that the refrigerating unit is completely encircled by the air passageways, and air passing therethrough will be entirely chilled before it is discharged from the lower end of the duct 20 55

at the bottom of the food chamber 2 of the refrigerator. The duct 20 extends down between the shelves 5 and the side wall of the refrigerator nearest the refrigerating unit and the lower end 5 of the duct is joined to one edge of the corrugated baffle plate 21 which extends across and in spaced relation with the bottom of the food chamber. The corrugations of the plate 21 extend from the front to the rear of the food chamber and 10 thus parallel the lower edge of the downwardly directed air duct. The baffle may be mounted upon parallel supports at the front and rear of the food chamber such as are conventionally shown and indicated by the numeral 22a, or upon any 15 other suitable supporting means.

The side walls of the corrugations of the baffle plate 21 are provided with apertures 22 and secured to the underside of the corrugated baffle plate are the two horizontally disposed plates 23 20 which have their free edges directed toward the air discharge end of the vertical duct 20 and are positioned substantially in the middle of the area between the bottom of the food chamber and the underside of the plate 21. Thus, it will be seen 25 that with these horizontal division plates 23, the air flowing downwardly through the duct 20 will be divided as illustrated by the arrows and will flow beneath and over the top of the plates 23 and thereby be evenly distributed under the baffle plate 21 from beneath which it will flow 30 upwardly through the apertures 22. The air will then rise through the food chamber, as indicated by the flow arrows, and will pass through the outer one of the openings 13a at the top of the 35 deodorizing and gas removing unit and flow downwardly past the baffles 16 and through the baffle screen 14 and then into the ducts 17 and 18 to repeat the circuit by way of the duct 20.

It will be readily understood that this circulation 40 will be maintained because of the natural tendency of cold air to seek the lowest level and of warmer air to rise and thus the naturally formed current of air will pass over the fluid in the receptacle 11 and through the absorbent material 15 in 45 the screen 14 so that absorbed food odors will be removed from the air before it is again circulated through the food chamber.

I claim:

1. In a refrigerator structure of the type having 50 a food chamber and a refrigerating unit in the upper part of the chamber, means forming an air duct across a side of the refrigerating unit, an air duct extending vertically through the food chamber at one side thereof for connection at its upper 55 end with said first duct, means in the lower part of the food chamber for receiving air from the lower end of the second mentioned duct and distributing it over and discharging it upwardly throughout the area of said chamber, and means 60 at the top of said chamber for guiding air into the first mentioned duct.

2. In a refrigerator of the character having 65 a food chamber and a mechanical refrigerating unit in the upper part of the chamber, means forming an air duct completely about the unit, said air duct having an air inlet adjacent the top of the unit and an air outlet adjacent the bottom of the unit and upon the opposite side thereof from the inlet, a vertically disposed air duct leading 70 downwardly from said outlet and discharging in close proximity to the bottom of said food chamber, a horizontally disposed plate substantially covering the area of the bottom of said food chamber and having the discharge end of the last mentioned duct opening therebeneath, said plate hav-

ing a plurality of apertures therethrough for the upward escape of air whereby the air discharged therebeneath will be evenly distributed throughout the interior of the chamber.

3. In a refrigerator of the character having a food chamber and a mechanical refrigerating unit in the upper part of the chamber, means forming an air duct completely about the unit, said air duct having an air inlet adjacent the top of the unit and an air outlet adjacent the bottom of the unit and upon the opposite side thereof from the inlet, a vertically disposed air duct leading downwardly from said outlet and discharging in close proximity to the bottom of said food chamber, a horizontally disposed corrugated plate 15 arranged in close proximity to the bottom of said food chamber with the corrugations extending across the width of said last mentioned air duct and having the outlet end of the air duct arranged to discharge air beneath the plate, said plate 20 having apertures therethrough, and baffle means disposed in the area between the plate and the bottom of the food chamber for effecting the equalized distribution of air beneath the plate.

4. In a refrigerator having a food chamber and 25 a mechanical refrigerating unit in the upper part thereof, a receptacle having air inlet and outlet openings adjacent the top part thereof and disposed in close proximity to said unit, an absorbent screen disposed vertically in the receptacle between 30 said inlet and outlet openings, the receptacle being adapted to contain a gas absorbing liquid, an air duct leading from the outlet of the receptacle across a side of said refrigerating unit, a downwardly extending air duct having its upper 35 end connected with the first mentioned duct and having its lower end arranged to discharge air in close proximity to the bottom of the food chamber, and means adjacent the bottom of the food chamber for effecting the equalized distribution of 40 air thereover for discharge upwardly through the entire area of the chamber.

5. In a refrigerator having a food chamber and a mechanical refrigerating unit in the upper part thereof, means forming air ducts around said unit, 45 said air duct forming means having an air inlet adjacent the top of the unit and an air outlet adjacent the bottom of the unit and upon the side opposite from the air inlet, a receptacle supported in the upper part of the food chamber and 50 adapted to contain a gas absorbing and deodorizing liquid, said receptacle having an air inlet and an air outlet, the receptacle air outlet being connected with the inlet of said air duct, baffle means within the receptacle for effecting the forced circulation of air across the liquid contained in the receptacle in the passage of the air to the receptacle outlet, means for conducting air from the air duct outlet to and discharging it at the bottom 55 of the food chamber and means disposed over the bottom of the food chamber for effecting the equalized distribution over said bottom of the air discharged from the said conducting means.

6. In a refrigerator having a food chamber and a mechanical refrigerating unit in the upper 65 part thereof, means forming air ducts around said unit, said air duct forming means having an air inlet adjacent the top of the unit and an air outlet adjacent the bottom of the unit and upon the side opposite from the air inlet, a receptacle supported in the upper part of the food chamber and adapted to contain a gas absorbing and deodorizing liquid, said receptacle having an air inlet and an air outlet, the receptacle air outlet being connected with the inlet of said 70

air duct, a pair of spaced baffle plates disposed vertically within said liquid receptacle and extending downwardly from the top thereof a substantial distance below the said air inlet and outlet of the receptacle, an absorbent screen disposed centrally between said baffle plates in the receptacle and connected with the top of the receptacle and extending downwardly a substantial distance below the lower edges of said baffle plates, means for conducting air from the air duct outlet to and discharging it at the bottom of the food chamber and means disposed over the bottom of the food chamber for effecting the equalized distribution over and upwardly from said bottom of air discharged from the said conducting means.

7. In a refrigerator having a food chamber and a refrigerating unit in the upper part thereof, means forming an air duct having an inlet adjacent the top of the food chamber and extending across and in close proximity with the refrigerating unit to an adjacent side wall of the chamber, a downwardly extending duct connected at its upper end with the first duct and discharging into the chamber at the bottom thereof, a corrugated plate disposed in close proximity to said chamber bottom and substantially covering the area thereof, the discharge end of said second duct being below said plate and said corrugations extending parallel with the width of the adjacent duct, said plate having apertures therethrough for the upward flow of air, and horizontally disposed baffle plates carried between the first plate and the said bottom of the chamber for effecting the equalized distribution over the underside of the corrugated plate of air discharged from the lower end of the adjacent duct.

8. In a refrigerator having a food chamber and a mechanical refrigerating unit in the up-

per part thereof, means forming an air duct across a side of the refrigerating unit, the air duct having an air inlet adjacent the top of the unit and an outlet adjacent the lower side of the unit, an air duct extending downwardly through the food chamber and having its upper end connected with said outlet and having its lower end arranged for the discharge of air into the chamber adjacent the bottom thereof, air distributing means extending across the said bottom of the chamber at an elevation above the lower end of said downwardly extending air duct whereby air issuing from the latter will flow beneath said means, said air distributing means being so constructed and arranged that the air discharged therebeneath will flow upwardly therethrough and be equally distributed over the entire area of the chamber, and means interposed between the said inlet of said air duct and the air discharge outlet in the lower part of the chamber for absorbing odorous gases carried by air entering the said air inlet.

9. In a refrigerator structure of the type having a food chamber and a refrigerating unit in the upper part of the chamber, means forming an air duct extending from the upper part of the food chamber to the lower part thereof, the said air duct having an inlet at its upper end and an outlet at its lower end and being constructed and arranged with respect to the refrigerating unit to cause air flowing therethrough to be brought into contact with the unit, means in the lower part of said chamber for distributing upwardly through the entire area of the chamber the air discharged from said outlet, and deodorizing means arranged in the upper part of the chamber over said air inlet through which means air must pass before entering the said inlet.
